H. C. MARTIN.
SOUND BOX FOR PHONOGRAFS.
FILED JAN. 23, 1922.

Inventor

HENRY C. MARTIN

C. C. Clements.

Attorney

UNITED STATES PATENT OFFICE.

HENRY C. MARTIN, OF ELKHART, INDIANA.

SOUND BOX FOR PHONOGRAHS.

Application filed January 23, 1922. Serial No. 531,232.

To all whom it may concern:

Be it known that I, HENRY C. MARTIN, a citizen of the United States of America, residing at Elkhart, in the county of Elkhart 5 and State of Indiana, have invented certain new and useful Improvements in Sound Boxes for Phonographs, of which the following is a specification.

The present invention relates particularly 10 to certain improvements in instruments of the phonograph type involving the sound conveying members which include the conveyer arms between the stylus and diaphragm of the sound box, and the tone arm 15 or tubular sound conveyer between the sound box and the amplifying member or amplifier, together with other correlated improvements as will be hereinafter more specifically pointed out and claimed. By the 20 utilization of my invention sound conveying means are provided for accurately recording and reproducing sounds or tones with full measure and value that are clear and life-like, and with the original full volume.

25 To this end the invention relates particularly to the construction of the sound conveying members, which are of increasing conveying capacity, from the needle or stylus to the amplifier. The thickness of the 30 material of the walls of the conveyers also increases uniformly and gradually from the smaller end of the sound conveyer to the larger end, as will be hereinafter specified and claimed.

35 In the accompanying drawings I have illustrated one complete example of the physical embodiment of my invention wherein the parts are combined and arranged according to the best mode I have 40 thus far devised for the practical application of the principles of my invention.

Figure 1 is a top plan view, partly in section, of the adjustable, telescopic tone arm, showing also the sound box, and tone-modifying adjustable slide.

45 Figure 2 is a side view of the device of Figure 1, partly in section.

Figure 3 is a sectional view at line 3—3 of Figure 2 illustrating the form and arrangement of the sound conveyer arms.

50 Figure 4 is a transverse sectional view of the sound box showing the diaphragm and the means of attaching the conveyer arms thereto.

55 In the preferred form of the invention as shown in the drawings, the sound box des-

ignated as a whole by the numeral 1 is attached to the tone arm and disposed at an angle to the plane of the record disk carried on the turntable of the phonograph 60 not shown, but which may be of suitable construction. The angularly disposed sound box thus travels across the face of the disk in usual manner for recording and reproducing sounds. In Figure 4 it will 65 be seen that the box includes a metallic circular base plate 2 having an open center for attachment of the elbow or bend 3 of the tone arm 4, and the metallic elbow is fashioned with an exterior, annular collar 70 or flange 5 to be encased within the retaining head 6, there being interposed between the flange and head suitable non-conducting gaskets or rings 7. The plate, head, and elbow are secured firmly together by means 75 of screws 8 passing through the flanged head and the base plate as shown.

The diaphragm 9 of the sound box is preferably of mica, and is of peculiar and novel construction. It is in the form of a circular disk, concavo convex in shape with its concavity toward the reproducing or recording stylus, and its maximum thickness at its radial center, adjacent to the opening in the elbow of the tone arm. The edges 80 of the diaphragm decrease in thickness toward the periphery thereof, and this formation, together with the concavo-convex structure of the diaphragm, which is of course resilient, insures a movement of the 85 sound vibrations or waves in a more concentrated or central direction toward the outlet or opening of the sound box when recording, and toward the inlet opening when reproducing, from whence the vibrations or waves are distributed. The comparatively thin edges of the diaphragm are 90 retained and secured to the base plate of the sound box, by a flanged retaining ring 10, and here also non-conducting gaskets, 95 of rubber or other suitable material, are interposed between the diaphragm and its retaining ring, to prevent radiation of sound, and the retaining ring is secured to the underside of the base plate by screws 11.

Associated with the sound box are a multiplicity of sound conveying arms, here indicated as five in number and designated respectively 12, 13, 14, 15, and 16, the arms increasing in capacity for conveying sound 100 waves or vibrations. These arms are of resilient metal, and formed into helical coils 110

similar to springs, and the succeeding arms from 12 through 16 are composed of wire of increasing gauge and constitute successively heavier and less resilient conveyers, although all of the conveyer arms are resilient to some extent. The lower end of each of the arms, as indicated at 17 is brought to form an integral part of the stylus holder 18, of usual form, and the needle 19, which, because of the angular position of the sound box, is also disposed at an angle to the plane of the record, travels in the groove as usual, and is secured by the set screw 20 in the holder.

15 The upper end of each of these conveyer arms, as 21, is secured in the diaphragm by means of upper and lower clamp nuts 22 and 23 as seen in Figure 4. The several conveyer arms are disposed about the center of the 20 diaphragm, between the latter and the stylus holder, and are arranged symmetrically with their respective upper and lower ends brought into close formation. The conveyer arms differ, not only in the diameter of their coils and gauge of thickness of the wire forming the coils, but they differ in length of wire between the stylus and the diaphragm and the wire may increase in thickness toward the stylus.

25 30 The conveying or transmitting arms leading from the stylus or needle to the diaphragm, where they are centrally located at the maximum thickness of the diaphragm insure a maximum force of vibrations on the diaphragm, thereby influencing the vibrations to greater action in their course of development and amplification in the tapered tone arm 4 for reproduction, and from the diaphragm to the record in recording sounds.

35 40 The tone arm 4 is also designed with this purpose in view, and is adjustable as to its length for adapting it to different conditions, thereby bringing the voice or sound to be recorded closer to the diaphragm and record, thus enhancing or increasing the force of the vibrations at the recording point, resulting in a deeper and clearer record produced by the needle.

45 50 As best seen in Figs. 1 and 2 the tone arm is a telescopic structure, and includes an inner tubular section 24 having a split end sleeve 25 with perforated ears 26, and a clamp screw 27 by means of which the sleeve, which embraces the upper end of the sound box elbow 3, is secured thereto in adjusted position for properly locating the sound box and needle on the record. The exterior, telescopic tube or section 28 embraces the section 24 and is movable thereon, to extend or contract the length of the tone arm, there being sufficient frictional engagement between the parts to hold the sections of the tube in adjusted location. The cross area, 55 or interior diameter of the tone arm in-

creases with its distance from the sound box, and the material in, or the thickness of the walls of the tone arm also increases with the distance from the sound box. The outer end of the tone arm is embraced by a sleeve 29 of the horizontally disposed elbow 30, the frictional contact between the sleeve and arm being such as to hold the parts in proper relation, and a vertically disposed elbow 31 having an end sleeve 32 surrounds the reduced extension 33 of the horizontal elbow 30. The lower end 34 of the vertical elbow is encased within the larger sleeve 35 of the third elbow 36, and these three elbows, which form the connection between the tone arm proper and the amplifier, also have the ratio of their interior diameter, and the ratio of the thickness of their walls, increased with the distance from the sound box.

55 60 Between the tone arm above the record and the amplifier beneath the record, I employ a tone modifier, joining the ends of the divided amplifier and adapted to be extended or contracted in linear direction, to provide deeper or lower tones, and lighter or higher tones respectively. Usually this result is accomplished in phonographs by increasing or diminishing the speed of the revolving or rotating record, and is objectionable for the reason that the tempo or time is unduly altered. By the utilization of my modifier, the tempo or time is not changed, although the tone is modified as desired.

65 70 The structure employed in the tone modifier involves the free end 37 of the elbow 36, a horizontally disposed U-shape tubular member having legs 38 and 39, and the intermediate bend 40, co-acting with said end 37 and a complementary end 41 of the amplifier, a portion of which is indicated as 42. In Figure 2 the modifier may be pulled outwardly or to the right to extend or elongate the amplifier at this point, or in similar manner, the modifier may be moved to its contracted position, as in the drawing, the tubes 38 and 39 sliding on the tubular ends 37 and 41.

75 80 The gradual and uniform increase in the diameter of the conveyer or tone arm from the sound box through the tuning slide, and the corresponding thickness of the walls of the sound conveyer, assist in the development or amplification of the partials or fractions of sounds, before they reach the amplifier, and stimulate the action of the sound waves, thus rendering their production more facile.

85 90 It will be understood that the length of the tone arm may be extended or contracted through the relatively movable inner section 24 and outer section 28, and that the tone arm bodily swings on the swivel joint 34-35 beneath the elbow 31, as usual.

95 100 Having thus fully described my inven-

tion, what I claim as new and desire to secure by Letters Patent is—

1. The combination with a diaphragm, of a sound box and stylus holder, of a plurality of transmitting arms varying in length and composed of various but uniform thicknesses and each having their respective ends connected with diaphragm and stylus holder.
- 10 2. The combination with the diaphragm of a sound box and a stylus, of tone transmitting arms of dissimilar degrees of resiliency, varying in length, and composed of various but uniform thicknesses and each 15 having their respective ends attached to said diaphragm and stylus.
- 15 3. The combination in a recording and

reproducing instrument including the diaphragm and stylus, of a plurality of tone transmitting arms varying in length and 20 formed in helical coils of different diameters, each having its respective ends attached to said diaphragm and stylus.

4. The combination in a recording and reproducing instrument including a stylus 25 and diaphragm, of a plurality of resilient tone-transmitting arms varying in length and forming helical coils of different diameters and composed of various but uniform thicknesses, and each said arm having its 30 respective ends attached to said diaphragm and stylus.

In testimony whereof I affix my signature.

HENRY C. MARTIN.
